APPARATUS FOR RIPPING OR TEARING RAW
TOBACCO LEAVES INTO PIECESOswald E. Eissmann, Brook Hill, Va., assignor to
J. C. Muller, Inc., Richmond, Va., a corpora-
tion of Virginia

Application July 1, 1939, Serial No. 282,335

9 Claims. (Cl. 131—146)

This invention relates to an apparatus for ripping or tearing raw tobacco leaves into pieces, and more particularly provides improvements over the structure shown in the former Patent No. 2,127,329 of August 16, 1938.

In contrast to the former structure, the present structure causes the leaves as they are ripped to be divided into two divergent paths, one a lower path as heretofore, and one an upper path. By so dividing the paths of operation, a better sized leaf is obtained, the end product being of more uniform size and with less fine tobacco.

Furthermore, the invention also has in mind the subjection of the tobacco to a periodic intermittent feeding instead of having such feeding continuous.

This invention consists of a machine into which raw tobacco leaves are put and shredded into tobacco flakes as large as possible without any stem pieces on them and also producing entirely clean stems. The stems with adhering tobacco do not have to run through the machine again as heretofore, sometimes several times, until the stems are clean, and this, of course, is a disadvantage, as every run will tear the adhering tobacco pieces more and make smaller sized flakes. For this purpose, the machine operates to divide the tobacco into two paths, each in a different direction, and to have the loosening members unsurrounded by any plate. The tobacco is acted upon in opposite directions. The speed of the cleaning devices is higher than that of the loosening devices.

The invention further consists of means for intermittently feeding the tobacco to the machine so that the ripping action takes place only upon those parts which have been fed into the machine, and the operation of ripping is substantially completed, before the feeding again takes place.

The invention will be more fully described hereinafter, embodiments thereof will be shown in the drawings, and the invention will be finally set forth in the claims.

In the accompanying drawings:

Figure 1 is a side view of the structure embodying my invention;

Figure 2 is a diagrammatic drawing showing the mechanism used to set the structure shown in Figure 1 in operation, with the possibility of feeding the tobacco intermittently or periodically;

Figure 3 is a partial side view of a loosening member and a cleaning drum, with the comb and tooth laterally engaging each other;

Figure 4 is a partial plan view of a loosening member and a cleaning member, showing the disposition of the combs and teeth, the shape of the combs and teeth being shown arbitrarily, merely as an example;

Figure 5 is a plan view of a leaf of tobacco showing the manner in which parts thereof are successively torn away;

Figure 6 is a cross section of a stem showing how the parts of the leaf that remain after some parts have been ripped are bent in one direction in respect to the stem by the operation of the lower loosening member; and

Figure 7 is a similar section showing how the parts of the leaf are bent in the opposite direction in respect to the stem, due to the operation of the upper loosening member.

Similar characters of reference indicate corresponding parts throughout the various views.

Referring to the drawings, and more particularly to Figure 1, a substantially horizontal platform 2a is provided over which a feed belt 2, passing over pulleys 2b and 2c, is moved in the direction of the arrow 1, the rotation of the pulley 2c being indicated by the arrow 1a. Superimposed pulleys 4 and 5 rotating in the directions of the arrows 4a and 5a and supported upon shafts 4b and 5b, serve to grip the tobacco leaves and feed them forwardly. Disposed between the conveyor roll 2c and the lower roll 5 is a bridge 3 which receives the tobacco leaves fed by the conveyor 2. At the other side of the superimposed rolls 4 and 5 there is another bridge marked 6, substantially like the bridge 3, to receive the tobacco moved forward by the rolls 4 and 5 and to support the tobacco as upon an anvil when loosening members 8 and 9 go into action, during which time the tobacco is still held by the compression of the rolls 4 and 5. Both of these bridges 3 and 6 have an upper surface substantially straight and horizontal and have each downwardly converging surfaces of curved shape corresponding substantially with the curvature of the roller 2c, the roller 5 and in general to the path of movement of the combs 10 of the loosening member 9.

The loosening member 8 rotates in the direction of the arrow 8a, and the loosening member 9 rotates in the direction of the arrow 9a, that is, in opposite direction. A guide wall 30 is supported by the casing 31, which guide wall in the event of any tobacco parts being thrown by the loosening member 8, serves to guide such parts upon the bridge 6, whereupon they are again subjected to the action of the members 8 and 9.

Another guide wall 33 is also secured to the upper part of the casing 31, and this serves to guide any material downwardly to a cleaning drum 11 having combs 12, and this cleaning drum 11 rotates in the direction of the arrow 11a and is surrounded by a grate 13 having bars 14 and openings 15 through which the ripped tobacco and cleaned stems fall. The grate 13 is suitably secured to the parallel end walls 32 of the casing, and extends across the end walls. This is not shown in the drawings, but is known in the art. At one side of the path of rotation of the loosening member 8, a guide wall 34 is arranged having a curved upper portion 35 which extends between the path of rotation of the loosening member 8, and the path of rotation of the cleaning drum 11, and the lower end of the grate 13. A downwardly extending part 35a is inclined to the vertical, and extends close to a grate 20 surrounding a cleaning drum 16 in order to guide tobacco between the grate 20 and the drum 16. The cleaning drum 16 rotates in the direction of the arrow 16a, and has combs 17. The grate 20 has openings 18 and spaced bars 19 for the passage of the tobacco. For a like purpose, there is disposed at the other side of this cleaning drum 16 another guide wall 36 substantially vertical and having an outwardly bent over portion 37 to receive any parts of tobacco which may fall down from the conveyor 2 or from the bridge 3.

It is within the knowledge of a man skilled in the art to provide means for operating the devices shown in Figure 1. The various shafts are supported in the parallel end walls 32 as known. A diagrammatic drawing of the transmission means is shown in Figure 2. A motor 40 has a belt 41 setting in operation the drum shaft 43 over pulley 42. Upon the shaft 43 is a pulley 44 having an endless belt 45 over pulley 46 mounted on stop shaft 47, and another pulley 48 on shaft 49, and passes over pulley 50 on drum shaft 51. On shaft 49 is a spur gear meshing with gear 53 on shaft 54. A gear 55 on shaft 66 meshes with gears 52 and 67. Gear 67 on shaft 4b meshes with gear 68 on shaft 5b. Between this gear 68 and the gear 70, a pinion 69 is placed which may be moved into mesh or out of mesh of the gears 68 and 70. Gear 70 is mounted on shaft 72 which drives the feeding roll 2c. When this pinion gear 69 is in mesh with the gears 68 and 70, the feed is continuous. When the gear 69 is out of mesh, the feeding of the conveyor belt 2 is interrupted. The other parts, however, carry on with their movement and strip the tobacco which is within the path of operation of the parts of its leaf, and thereafter when the gear 69 has been brought into mesh, a new supply of tobacco is provided by the conveyor 2. As before stated, various means may be provided to operate these shafts. Instead of the pinion 69 any other device may be used within the knowledge of a mechanic, such as a clutch or a Geneva.

An important point of the improvement, however, is that, on the one hand, the feeding of the leaves is intermittent if so desired; and, on the other hand, the cleaning drums rotate three times faster than the loosening members. The loosening members and the cleaning drums run in a ratio of 1 to 3.

It is also important as part of the improvement, to have an upper path and a lower path for the ripping of the leaves. Whereupon, clean ribs in one operation of the machine are provided with larger pieces. In other words, the

ripping of the tobacco leaves is done in opposite directions, the upper loosening member 8 stripping the leaves at substantially right angles to said leaves in a downward direction and conveying the loosened parts to an upper cleaning drum 11 having combs 12, while the lower loosening member 8 stripping the leaves at substantially right angles to the latter but in an upward direction and conveying the loosened parts to a lower cleaning drum 16 having combs 17.

The operation is as follows:

The tobacco leaves are fed in the direction of the arrow 1 on the feed belt 2. The tobacco so fed passes the bridge 3 and is forced into the bight of the compression feed rollers 4 and 5. After passing through them, the tobacco leaves pass over the bridge 6, and its acute corner 7, and project therefrom entering into the bight of the paths of the combs 10 of the loosening members 8 and 9. The upper loosening member 8 rotates in one direction, anti-clockwise, and takes off part of the tobacco leaf at each side of the stem in sizes as the leaf stands over the corner 7 of the bridge 6. In Figure 5 a leaf is shown. The combs 10 enter it along line A—A, as shown by the pierce holes 71. In order not to bend the stems with adhering leaf parts down too far, the center of the loosening member 8 is placed above the horizontal input line for the raw tobacco. Upon the downward movement of the combs 10 of the member 8, the parts 82 of the leaf not ripped off, are moved downwardly in respect to the stem 80, as shown in Figure 7. The second loosening member 9 with combs 10 rotates in the opposite direction from the loosening member 8, (in clockwise direction) and lifts the tobacco stems with adhering leaves, ripping off along line B—B when the machine is running continuously, leaving parts 81 bent upwardly as shown in Figure 6. The upwardly bent parts 81 are forced upwardly by the combs of the member 9. If the feed action is intermittent, then the parts 82 on the stem in advance of line A—A are only acted upon, and no further leaf stripped off. This alternate action of down and up, or up and down, as the case may be, of the remaining parts, cleans them from the stem. In other words, the part of the tobacco stem which stands over the outstanding corner 7 of the bridge 6 will be well cleaned by actions in both directions, as the leaf stem always stays substantially horizontal. Thus, as the combs 10 of loosening member 8 force the remaining parts of the leaf down while taking the larger part of the tobacco flakes off, the combs 10 of the loosening member 9 will force the leaf upwardly again, and will take the rest of the adhering leaf off the stem, while taking off a fresh part of the progressively advancing leaf. The free edges of the combs of each loosening member partake of an orbit or path of rotation, as shown in the dot-dash lines. These intersect. The end 7 is substantially at the point of intersection, but outside of the orbits. The axis of rotation of the member 8 is above the end 7, and the axis of rotation of the member 9 is below the end 7. Neither loosening member has a curved plate, as heretofore used. To prevent the tobacco from breaking up to a certain extent which is not wanted, after having been taken off the stems, the improvement also consists in the omission of a curved plate heretofore used, below a loosening member, which plate stops the tobacco from dropping down vertically by gravity. As the tobacco is now free to fall by gravity, a tearing of the tobacco is avoided, since no curved plate is used.

Further, practice has shown that if very small tobacco flakes are wanted out of whole leaves, a grate has to be provided with small sized holes or slots in order to obtain the required size. In doing so, the whole shredding chamber with a curved plate became more or less crowded with tobacco as the flakes taken off by the teeth on the loosening member are still too large to drop freely through the grate. Therefore, the flakes including the long and some broken stems with adhering leaves were forced around by the beating drum, and when the teeth of the beating drum were going through the teeth of the loosening member, such flakes and stems were made shorter. However, due to the fact that the teeth of the loosening member were always bringing new tobacco which is supplied to the machine and taken off on the uppermost corner of the curved plate around the loosening member, the whole chamber became crowded with tobacco. All of the tobacco pieces mixed with long and short stems with adhering leaf and the loose flakes rubbed against each other in the chamber until they were small enough to go through the small holes in the grate. As a result, the tobacco was not only shedded into small flakes, but much of the tobacco was broken due to the fact that the whole chamber was too crowded, and by rubbing against each other small flakes of tobacco were broken which were already of the correct size but did not have a chance to drop through the small holes in the grate heretofore used. In other words, the known equipment made too much fine tobacco due to the rubbing effect which is not wanted. It is known that the larger the leaf fragment the more valuable the tobacco. The object here is to keep the size of the tobacco scrap produced as near as possible to the size required.

The improvement, which utilizes two loosening members 8 and 9, each with combs 10, splits the quantity treated. The combs 10 of loosening member 8 take off a certain amount of tobacco standing over the edge 7 on the bridge 6 and take it over to the cleaning drum 11 which has combs 12. The cleaning drum 11 revolves exactly opposite to the loosening member 8 and at a higher speed. With the higher speed, the combs 12 of the cleaning drum 11 take off the tobacco flakes sitting in the teeth of the combs 10 on the loosening member 8 with very little breakage and then, force said flakes against grate 13 or its bars 14 so that they can drop through the openings 15 without being rubbed against each other. The second loosening member 9 with the combs 10 takes off the rest of the adhering leaf on the outstanding stem over the corner 7 of the bridge 6 and take it downwardly to the second cleaning drum 16 with combs 17 which also take out the tobacco flakes hanging in the combs 10 of the second loosening member 9. As the second cleaning drum 16 is also working with a higher speed than the second loosening member 9, it will take out the tobacco flakes hanging in the teeth 10 of the second loosening member 9 without much breakage and throw them against the second grate 18 with bars 19 or through the opening 20. In other words, the whole amount of tobacco to be shredded is split into two portions and therefore each one of the shredding chambers is not so crowded and the new invention makes a much better product of more uniform size with much less fine tobacco. Further, due to the two loosening members in the new invention, the quantity of tobacco will be split, which avoids a crowded separating chamber and thereby avoids the rubbing together of the to-

bacco which practice has shown makes a much better product with more uniform size with less fine tobacco.

5 A further improvement consists in working the feed belt 2 periodically. Practice has shown that very large tobacco flakes can be produced from whole leaves. When working periodically the combs 10 of the two loosening members 8 and 9 will take off large flakes from the raw tobacco 10 in lengths as overstanding the point 7 on the bridge 6 and when working periodically, after the large flakes are taken off the stems by the loosening members 8 and 9, the cleaning members, due to their higher speed of rotation, will 15 clean the tobacco stem thoroughly before the periodic transportation again is set into working.

The invention consists in the absence of curved plates around the loosening members; in the twin paths of treatment; in the opposed directions 20 of treatment; in the higher speed of the cleaning members over that of the loosening members, and in the periodic or intermittent transportation of the tobacco supply.

I have described an embodiment of my invention, but it will be clear that changes may be made within the principle of the invention described without departing from the scope of the subjoined claims.

What I claim is:

30 1. An apparatus for ripping or tearing raw tobacco leaves into pieces, comprising a feed device, a first rotary loosening device, a second rotary loosening device below the first loosening device, both loosening devices having combs, each 35 comb acting at substantially right angles to the leaves fed by the feed device, and a rotary cleaning device for each loosening device, said rotary cleaning devices cooperating with respective loosening devices to convey the stripped tobacco in 40 separate paths.

2. An apparatus for ripping or tearing raw tobacco leaves into pieces, comprising a feed device, a first rotary loosening device, a second rotary loosening device below the first loosening device, both loosening devices having combs, each 45 comb acting at substantially right angles to the leaves fed by the feed device, a rotary cleaning device for each loosening device, said rotary cleaning devices cooperating with respective loosening devices to convey the stripped tobacco in 50 separate paths and means for rotating the cleaning devices faster than the loosening devices.

3. An apparatus for ripping or tearing raw tobacco leaves into pieces, comprising a feed device, a first rotary loosening device, a second rotary loosening device below the first loosening device, both loosening devices having combs, each 55 comb acting at substantially right angles to the leaves fed by the feed device, said loosening devices rotating in opposite directions and dividing the stripped tobacco into two paths, one upwardly and one downwardly, a rotary cleaning device cooperating with the first loosening device and moving the stripped tobacco further in the upper path, and a second cleaning device cooperating with the second loosening device and moving the stripped tobacco further in the lower path.

4. An apparatus for ripping or tearing raw tobacco leaves into pieces, comprising a feed device, a first rotary loosening device, a second rotary loosening device below the first loosening device, both loosening devices having combs, each 60 comb acting at substantially right angles to the leaves fed by the feed device, said loosening devices rotating in opposite directions and dividing the stripped tobacco into two paths, one up-

wardly and one downwardly, a rotary cleaning device cooperating with the first loosening device and moving the stripped tobacco further in the upper path, a second cleaning device cooperating with the second loosening device and moving the stripped tobacco further in the lower path, and a grate having openings for the passage of the stems and stripped tobacco, partially surrounding each cleaning device.

5. An apparatus for ripping or tearing raw tobacco leaves into pieces, comprising a feed device, a first rotary loosening device, a second rotary loosening device below the first loosening device, both loosening devices having combs, each comb acting at substantially right angles to the leaves fed by the feed device, said loosening devices rotating in opposite directions and dividing the stripped tobacco into two paths, one upwardly and one downwardly, a rotary cleaning device cooperating with the first loosening device and moving the stripped tobacco further in the upper path, a second cleaning device cooperating with the second loosening device and moving the stripped tobacco further in the lower path, a grate having openings for the passage of the stems and stripped tobacco, partially surrounding each cleaning device, and guide walls approximate each loosening and cleaning device for guiding the tobacco towards the same.

6. In an apparatus for ripping or tearing raw tobacco leaves into pieces, a pair of oppositely rotating loosening devices forming a bight for the tobacco to be loosened and dividing the stripped tobacco into two paths, a pair of oppositely rotating cleaning devices, one for each loosening device, said cleaning devices cooperating with the respective loosening devices to further advance said stripped tobacco in the respective paths; a feeding means for feeding tobacco to the bight of the loosening devices, and means for intermittently operating the feeding means, during the continuation of the operation of the loosening and cleaning devices.

7. In an apparatus for ripping or tearing raw

tobacco leaves into pieces, a pair of oppositely rotating loosening devices forming a bight for the tobacco to be loosened and dividing the stripped tobacco into two paths, a pair of oppositely rotating cleaning devices, one for each loosening device, said cleaning devices cooperating with the respective loosening devices to further advance said stripped tobacco in the respective paths and a feeding support for the tobacco entering to the entrance bight of the loosening devices having an edge at said entrance bight contiguous to the orbits of the extreme edges of the cleaning devices to enable the tobacco extending beyond the support and contiguous to said edge of the support to be acted upon in opposite directions by the loosening devices.

8. In an apparatus for ripping or tearing raw tobacco leaves into pieces, the combination of two oppositely rotating loosening members, alternately acting upon the tobacco, said loosening members dividing the stripped tobacco into two streams and bending the remaining part of the leaf in opposite directions in respect to the stem, and means feeding tobacco to such members.

9. In an apparatus for ripping or tearing raw tobacco leaves into pieces, the combination of a bridge having an upper horizontal surface, a loosening member having combs with edges, and having an axis of rotation above said surface, a second loosening member having combs with edges, and having an axis of rotation below said surface, one end of the bridge being immediately outside of the curved paths of the comb edges of the loosening members, and substantially at the point of intersection thereof, said end of the bridge cooperating with the comb edges of said first named loosening member to form a stationary support for the tobacco fed therefrom into the entrance bight formed by said curved paths of said loosening members, said bridge extending into said bight, save for contact with the comb edges during their rotation.

OSWALD E. EISSMANN.
